UNITED STATES PATENT OFFICE.

ABRAHAM J. MURCH, OF ST. LOUIS, MISSOURI.

TELESCOPIC CLOTHES-POLE.

No. 918,579.

Specification of Letters Patent. Patented April 20, 1909.

Application filed May 23, 1908. Serial No. 434,592.

To all whom it may concern:

Be it known that I, ABRAHAM J. MURCH, a citizen of the United States, and resident of St. Louis, Missouri, have invented certain new and useful Improvements in Telescopic Clothes-Poles, of which the following is a specification.

This invention relates to improvements in telescopic clothes poles and consists in the novel arrangement, construction and combination of parts as will be fully hereinafter described and claimed.

The object of my invention is to construct a clothes-pole arranged in sections and telescopic in form, one section of the whole being buried in the ground, the others adjusted at any desirable height from the buried section. The said pole when lowered being entirely out of the way.

Figure 1 is a side view of my complete invention, in its extended position. Fig. 2 is a sectional view of the same. Fig. 3 is a sectional view of the pole in its closed or collapsed position. Fig. 4 is a detail perspective view of the several parts in a partially extended position, and parts broken away showing its arrangement and construction. Fig. 5 is a horizontal sectional view of my invention when in its closed or collapsed position. Fig. 6 is a horizontal sectional view of a modified form of one of the sections showing it provided with a groove in the place of a slot.

In the construction of my invention, I provide a ground-member 7 provided at its bottom end with a suitable cap or inclosure 8, said ground member provided near its top with an inwardly projecting pin 9. In the ground member is slidably mounted a member 10 provided with an elongated slot or groove 11, the lower end of said slot or groove terminating into an offset and in said slot or groove projects the pin 9 of the ground member. The said member 10 is also provided near its top with an inwardly projecting pin 12. In said member 10 is slidably mounted a member 13 constructed in every detail similar to the member 10 and in the member 13 is slidably mounted the top section 14; its upper end provided with a cap 15 supporting a ring or eye 16 into which the end of the clothes-line may be fastened as well as permitting the operator to grasp the same for removing it from its collapsed position. Each of the members are slotted

with the exception of the ground member, the lower end of said slots terminating into an offset 17 into which the pins 12 project and support each member in its extended position; the construction and arrangement of 60 the slots and pins being clearly shown in Fig. 4.

The operation of my invention is as follows: The pole being composed of a plurality of members arranged to telescope one 65 within the other, is buried in the ground as shown in Figs. 1 and 2 and when it is desired to elevate or extend the pole, the operator by means of the rings 16 withdraws the first section 14 to the limit of the slot, 70 then by turning it slightly permits the offset in the slot to pass over the pin thereby retaining the section in a rigid extended position. The operator continues to elevate the section bringing with it the member 13 75 until the limit of its slot and this member is turned slightly until the pin and offset in the slot contact holding this member in a rigid extended position. The elevation is then continued until the member 13 is raised 80 and the operation of this is similar to the other two and the pole is then in a position ready for use. In lowering the same, the operator manipulates the several sections in a reversed movement to that previously described.

This construction of a device may be used as flag-staff hitching-post, or any other purpose found desirable but the essential feature is that of a telescopic clothes-pole.

As shown in Fig. 6, I show a modified form of section having a groove formed in the member instead of a cut slot, the operation, however, being similar in all respects.

Having fully described my invention, what I claim is:

A device of the class described comprising an outer imperforated tubular socket member closed at the bottom; a plurality of slotted tubular members of varying diameters arranged one to telescope within the other and all to telescope within the socket member, the slots having at their lower ends an upwardly extending offset portion, each of said members with the exception of the upper one provided with an inwardly projecting pin, each pin operating in the slot of the inclosed tube to hold the said tube elevated when the pin is in engagement with 105 110

the upturned portion of the slot and a cap mounted on the innermost tubular member serving as a cover for the socket member and intermediate tubular member so as to prevent foreign substances from entering into the members when the same are in a collapsed position, substantially as specified.

In testimony whereof, I have signed my name to this specification, in presence of two subscribing witnesses.

ABRAHAM J. MURCH.
